UNITED STATES PATENT OFFICE.

AUGUST SALICH, OF DENTON, TEXAS.

DESIGN FOR A TROUSERS-FASTENER MEMBER.

SPECIFICATION forming part of Design No. 28,646, dated May 17, 1898.

Application filed September 14, 1897. Serial No. 651,684. Term of patent 14 years.

To all whom it may concern:

Be it known that I, AUGUST SALICH, a citizen of the United States, residing at Denton, in the county of Denton and State of Texas, 5 have invented a new and original Design for a Trouser-Fastener Member, of which the following is a specification.

This invention relates to a new and original design for a trousers-fastener member; and it 10 has for its object to provide a design of this character that shall be both useful and ornamental.

The leading feature of the design resides in a trousers-fastener member provided with duplicate compoundly-curved edges converging to a common point, oppositely-inclined leaf-shaped openings, and a triangularly-arranged group of circular openings.

A minor feature of the design resides in the 15 trousers-fastener member having a flat body-plate folded into a substantial U form and provided at one side with an offset U-shaped hook lying parallel thereto.

In the drawings, Figure 1 is a perspective view of a trousers-fastener member embodying the herein-described design. Fig. 2 is a similar view showing the reverse side of the member. Fig. 3 is a cross-sectional view of the member.

Referring to the accompanying drawings, 30 the numeral 1 designates the body-plate of the trousers-fastener member, which is folded upon itself into a substantial U shape to provide duplicate parallel plate portions 2. The parallel plate portions 2 are provided with 35 compoundly-curved edges 3, converging to a common point 4, oppositely-inclined leaf-shaped openings 5, and with a triangularly-arranged group of small circular openings 6. One of said parallel plate portions 2 is further provided with superficial serrations 7, 40 following the compoundly-curved edges 3 and extending around the small circular openings and across the face of the plate. The other plate portion 2 is provided near the folded 45 edge of the body with an offset U-shaped hook 7^a, lying parallel thereto.

What I claim is—

The design for a trousers-fastener member herein shown and described.

In testimony that I claim the foregoing as my own I have hereto affixed my signature in the presence of two witnesses.

AUGUST SALICH.
